UNITED STATES PATENT OFFICE.

JOHN HERON, OF NEW YORK, N. Y.

WARCRAFT.

Application filed July 19, 1922. Serial No. 576,013.

To all whom it may concern:

Be it known that I, JOHN HERON, a citizen of the United States, residing at New York city, in the county of New York and State 5 of New York, have invented certain new and useful Improvements in Warcrafts, of which the following is a specification.

This invention has reference to war craft and particularly to a submarine for sinking 10 enemy vessels.

An object of the invention is to provide a submarine with means for attaching itself to the enemy's ship while submerged for the purpose of attaching an explosive there- 15 to, whereby the submarine is able to sink ships moving at a low speed or standing at anchor without having to appear on the surface of the water to accomplish such purpose.

20 A further object is to provide a submarine having a diver's compartment containing all necessary equipment for the sinking of an enemy's ship and an opening from the top of the submarine to permit the divers 25 to operate against the ship below which the submarine is submerged.

25 A further object is to provide a submarine which can be made much smaller than heretofore whereby they may be carried on the 30 deck of war ships and operated by any government at less expense.

Various other advantages and novel features of the invention will become apparent 35 from the following description.

35 In the drawing:

Figure 1 is a view in side elevation disclosing a submarine in attaching position with respect to a war ship, and

40 Figure 2 is a detailed view, on an enlarged scale, of the attaching end of one of the cables of the submarine.

Describing the invention in detail 45 designates the hull of the submarine, which, in the present instance, is provided with a diver's compartment 11, in which may be placed all the necessary equipment for the sinking of an enemy ship such as indicated at 12. Arranged below the diver's compartment and connected by a valved pipe 13 for a purpose hereinafter explained is a storage tank 14. Compartment 11 is provided with upper doors 15 and 16 and a lower door 17. These doors provide for the passage of one or more divers into or out 50 of the compartment when leaving or re-entering the submarine during a period in

which the latter is emerged. The compartment may be equipped with torpedoes for attacking a fast moving ship but when the ship is moving at a slow speed or standing 60 at anchor the submarine may be attached thereto by cables 18.

Each cable comprises as shown in Figure 2 an outer rubber tube 19 forming an insulation covering for magnet wires 20 and an inner rubber tube or air pipe 21. At its outer end, the cable is provided with a metallic collar 22 which carries a funnel shaped magnet 22 having teeth 24 to penetrate the side of the ship. The magnets of the cables 70 are energized from a suitable source 25 within the submarine and with which wires 20 connect as shown. The air tube 21 connects with a suitable suction pump 26 and has its outer end cleared and encased within magnet 23 as indicated at 27. When the magnets are energized and placed against the sides of the ship they serve to hold the submarine along side of the latter, thus enabling 75 the attachment thereto in a convenient manner of an explosive, such as a time-explosive bomb.

In practice, the divers being fully dressed and ready for work enter compartment 11 thru door 17 which is subsequently made secure to keep water from entering the submarine while the divers are at work. Doors 15 and 16 are then opened allowing the compartment to be filled with water, at which time the submarine would be close enough to ship 12 so as to allow the divers to attach cables 18 to the side of the ship in a forcible manner so as to cause the sharp pointed teeth 24 to force their way thru the paint, at which time magnets 23 are energized to hold the cable connected with the ship. The suction pump 26, may if needed, be also operated to hold the cables to the ship by suction. The cables, it will be noted, pass thru doors 15 and 16 and when not in use are stored in the compartments where they can be conveniently handled. In many instances the divers will not be required to proceed further than doors 15 and 16 of the compartment from which bombs and other 100 explosives can be readily affixed to the side of a ship. The water is subsequently forced out of the divers compartment by compressed air but if the compressed air fails 105 then doors 15 and 16 are closed and the water is released from the compartment into the emergency tank by way of pipe 16, the 110

divers remaining in the compartment until the water is completely discharged therefrom. Pipe 13 is preferably of a large diameter to provide for a quick outlet of the water and anchor 14 is of such capacity as to permit the diver's compartment to be entered three or four times while submerged so that at no time would the submarine have to appear at the surface of the water except 10 when the emergency tank is filled to capacity at such time the submarine may escape to a safety zone for the purpose of emptying the tank. It will thus be seen that the submarine is able to remain submerged for long 15 intervals and can thus attach without coming to the surface of the water. Hence, it

is able to accomplish its purpose without being visible to airplane or other crafts.

From the foregoing it is believed that the advantages and novel features of the invention can be readily understood and that further detailed description thereof is not required.

What is claimed is:

A war-craft including a submarine having 25 attaching cables provided with magnets for attachment to the side of an enemy vessel, said cable providing suction pipes whereby the cables may be attached by suction in the event of failure of the magnet.

In testimony whereof I affix my signature
JOHN HERON
